Patent 1,021,799

234X

Benzamin Franklin of Philadelphia

Letters Patent. dated Fez. 14. 1799.

The Schedule referred to in these Letters Patent and making part of the same containing a description in the words of the said Benjamin Franklin himself of an improvement being ~~described~~ in the said patent.

The weighing Steel yard or just Balance is made principally of iron & partly of Steel of any dimensions required for receiving the smallest or largest articles, from Gold coins to bags of sugar &c. The beam needs to be straight. The panes, or judgements and the circles in which they turn are of Steel, well tempered. The Beam is graduated on ~~one~~ edge with notches in which weights are hung as occasion may require. The pieces (or pieces as they are usually termed) may be made of lead, iron, brass or any other suitable metal, or even of stone. If made of lead they should be graduated by a beam or other durable rule to prevent reduction of weight by wearing off. Those who use the instrument all its parts should be preserved from corrosion. This Steel yard when constructed of the most convenient size, for family use, will weigh from one pound to two hundred and fifty. and one of the pieces must weigh two pounds and the other nine, &c. &c. every 10.1. on the beam producing a variation of two ounces with the small piece and one pound with the large, an equal dispensing weight. The pieces might be made of other sizes but these are the most convenient. The long arm of the beam is made sloping upward to nearly a right angle on which the weights are cast. On the two sloping sides are figures denoting the weight each being marked for the small pieces and the other for the large which must be added together when both pieces are on.

One Steel yard of this construction to weigh five hundred weight made only to have the parts made stronger and the large stone to weigh Ninety five. instead of fourteen pounds. doubling all the numbers on the large side of the beam. The notches with the third wood and

and produce a variation of displacement enough to obtain simple harmonic motion. The small force must be added and the sum of their weights taken as before. Other variations might be produced by the addition of more blocks. All the above is the simplest construction.

2. This is but one sufficient weight. A beam is balanced on one side of the center of motion to counterbalance the sum of all the forces, etc. to be hung. The center of motion is placed above the center of gravity & in a line with the points of suspension. By this means the beam vibrates like a scale beam. During the process of weighing an article is held above the weight as off the fulcrum being as much as possible reduced by terminating the suspension part of the fulcrum with sharp edges and using them in circles sufficiently large to prevent their touching on either side in turning. A proof of the accuracy of this balance is obtained by an experiment which can be made on no other beam with out instruments. It is as follows. By weighing any article sufficiently heavy to balance both pieces. (say 100 lbs.) The pieces may be put on one two numbers, which added together will produce 100; for example one piece may be put at 45 and the other at 10. or one at 93 and the other at 5. or one at 80 and the other at 20. Or at 78 and the other at 22. and so on throughout the extent of the beam. and if the beam moves step by accurate these numbers will perfectly correspond.
